W. RUTAN.

LOCKING DEVICE FOR HOISTING APPARATUS.

APPLICATION FILED APR. 28, 1915.

1,163,176.

Patented Dec. 7, 1915.

Inventor:
William Rutan,
by his attorney,
Charles R. Searle.

UNITED STATES PATENT OFFICE.

WILLIAM RUTAN, OF NEW YORK, N. Y., ASSIGNOR TO GILLIS & GEOGHEGAN, OF NEW YORK, N. Y., A FIRM.

LOCKING DEVICE FOR HOISTING APPARATUS.

1,163,176.

Specification of Letters Patent.

Patented Dec. 7, 1915.

Application filed April 28, 1915. Serial No. 24,425.

To all whom it may concern:

Be it known that I, WILLIAM RUTAN, a citizen of the United States, residing in the city of New York, borough of Queens, in the county of Queens and State of New York, have invented a certain new and useful Improvement in Locking Devices for Hoisting Apparatus, of which the following is a specification.

10 The invention relates to hoisting apparatus of the character described and shown in Letters Patent to Louis O. Forman, hoisting apparatus, dated April 30, 1912, No. 1,024,885, in which the hoisting-head is mounted to swing horizontally upon its standard, and the object of the invention is to provide a simple, efficient, easily operated device for automatically locking the hoisting-head to the standard during the 15 hoisting operation, and which shall extend outwardly but slightly and thus avoid the danger of fracture or derangement due to the rough handling to which heavy machinery of this class is subjected in transportation.

20 The invention consists in certain details of construction and arrangement by which the above objects are attained, to be herein-after described and claimed.

25 The accompanying drawings form a part of this specification and show the invention as it has been carried out in practice.

30 Figure 1 is an elevation of the upper portion of the hoisting apparatus, equipped with the improved locking device. The succeeding figures are on a larger scale and show the lock or latch with so much of the adjacent portions of the hoisting-head and standard as are necessary to show its relation thereto. Fig. 2 is an elevation as seen from the left in Fig. 1. Fig. 3 is a vertical section, partly in elevation, the plane of section being indicated by the line 3—3 in Fig. 2. Fig. 4 is a horizontal section taken 35 on the line 4—4 in Fig. 2, and partly in plan view.

Similar letters of reference indicate the same parts in all the figures.

40 A is a tubular standard arranged to slide telescopically in a vertical hollow post, not shown, and to be raised or lowered by suitable mechanism on such post, arranged to engage a rack A¹ on the standard, or otherwise. At the upper end of the latter is the 45 hoisting-head equipped with arms B B in

which is journaled a shaft C operated by a crank C¹ and carrying a pinion C² in mesh with the gear wheel D² on a shaft D mounted in the arms B B parallel with the shaft C, and carrying a winding-drum D¹ on which 50 is wound the cable M¹ by which the load M is lifted by turning the crank C¹. The hoisting-head may be understood to be supplied with a brake and other necessary equipments. The hoisting-head is rotatably 55 mounted on the standard so that it may be swung as required, and it is important that it remain fixed relatively to the standard while the crank is being turned in raising or lowering the load.

50 B² is a cylindrical shaft or stud firmly fixed in the boss B¹ of the head and received in the upper end of the tubular standard with liberty to rotate therein, the head being supported on an antifriction bearing or 55 step as at B³ to facilitate such rotation and permit the head to be swung when desired. In the stud B² is a radial cavity b containing a cylindrical latch F urged outwardly 60 radially to the stud by a helical spring G in the cavity, and held against escape therefrom by the engagement of a shoulder F¹ on the latch with an internal flange or lip b¹ formed by peening over the metal of the stud along the margin of the cavity after 65 the insertion of the spring and latch.

65 The nose F² of the latch is of less diameter than the body, thus forming a shoulder F¹, and is rounded on its end or outer face. In the locked position the nose F² enters and 70 engages in a hole a drilled radially in the standard in the proper location to register with the cavity b and insure the desired 75 position of the hoisting-head when thus locked.

80 H is a housing having flanges H² H² receiving bolts H³ H³ by which it is secured to the standard, covering the hole a and containing a push-pin J, and appears as a slight 85 protuberance or circular boss on the exterior of the standard. The push-pin J is held loosely in place by the engagement of a flange thereon, marked J¹, with an annular internal flange H¹ surrounding the opening 90 in the housing, and has a rounded projection 95 J² on the inner face arranged to be presented to and abut axially against the nose F², and force the latter inwardly by pressure of the hand applied upon the protruding portion 100 of the push-pin when the stud and 105 110

standard are locked and it is desired to release them. The projection J^2 is so shaped and proportioned as to enter the hole a as the latch is forced inwardly and bring the line of contact between the projection and nose into coincidence with the circumferential line of separation or joint between the stud B^2 and interior surface of the standard. While thus conditioned the hoisting-head with its stud may be rotated within the standard, the nose F^2 of the latch riding idly in rubbing contact with the inner surface of the standard. By turning the head again to the locking position, the nose F^2 automatically enters the hole a when presented thereto, forcing the push-pin outwardly and again locks the head in the hoisting position. The locking means is strong and reliable and adapted to resist the rough usage to which apparatus of the character is peculiarly liable, and as the housing and push-pin project but slightly, the apparatus may be shipped with the lock attached and in place ready for service, without danger of damage in transportation. The latch also aids in securing the head to the standard when locked thereto.

I claim:

1. In a hoisting apparatus, a tubular standard, a hoisting-head mounted to swing thereon and having a stud received therein, said stud having a radial cavity, and said standard having a radial hole located to register axially with such cavity when presented thereto by the rotation of said stud, an axially movable latch in such cavity, a spring in the latter arranged to urge said latch outwardly into locking engagement with such hole and means on the exterior of said standard for forcing said latch inwardly in opposition to such spring and out of engagement with such hole.

2. In a hoisting apparatus, a tubular standard, a hoisting-head mounted to swing thereon and having a stud received therein, said stud having a radial cavity, and said standard having a radial hole located to register axially with such cavity when presented thereto by the rotation of said stud, an axially movable latch in such cavity, a spring in the latter arranged to urge said latch outwardly into locking engagement

with such hole, a housing secured to said standard on the exterior thereof and covering such hole, and a push-pin slidable in said housing, having an inward projection arranged to enter such hole and abut against said latch and force it inwardly in opposition to said spring and out of engagement with such hole.

3. In a hoisting apparatus, a tubular standard, a hoisting-head mounted to swing thereon and having a stud received therein, said stud having a radial cavity with the edge of the latter peened inwardly to form a lip, said standard having a radial hole located to register axially with such cavity when presented thereto by the rotation of said stud, an axially movable latch in said cavity having a shoulder thereon adapted to engage said lip, and a nose adapted to enter and engage such hole, a spring in such cavity arranged to urge said latch and nose into such engagement, a housing secured to said standard on the exterior thereof and covering such hole, and a push-pin slidable in said housing, having an inward projection arranged to enter such hole and abut against said nose and force it and its latch inwardly in opposition to said spring and out of engagement with such hole.

4. In a hoisting apparatus, a tubular standard, a hoisting head mounted to swing thereon, said standard being mounted for vertical movement, a stud received in the upper end of said standard with liberty to rotate therein, said stud having a radial cavity and the standard having a radial opening, a radially movable latch in said cavity engageable in said opening, a spring in the cavity of the stud forcing the latch outward and a push pin movable inwardly against the outer end of said latch to force the latter inwardly to disengage it from the opening in the standard, and means within which said push pin is movable and by which it is prevented from outward displacement.

In testimony that I claim the invention above set forth I affix my signature, in presence of two witnesses.

WILLIAM RUTAN.
